US00D716819S

(12) **United States Design Patent**
Kotler et al.

(10) **Patent No.:** **US D716,819 S**
(45) **Date of Patent:** **** Nov. 4, 2014**

(54) **DISPLAY SCREEN WITH GRAPHICAL USER INTERFACE**

(71) Applicant: **Microsoft Corporation**, Redmond, WA (US)

(72) Inventors: **Matthew J. Kotler**, Sammamish, WA (US); **Erez Kikin Gil**, Redmond, WA (US)

(73) Assignee: **Microsoft Corporation**, Redmond, WA (US)

(**) Term: **14 Years**

(21) Appl. No.: **29/446,812**

(22) Filed: **Feb. 27, 2013**

(51) LOC (10) Cl. **14-04**

(52) U.S. Cl. **USPC D14/485**

(58) **Field of Classification Search**

CPC G06F 3/048; G06F 3/0481; G06F 3/0482; G06F 3/04812; G06F 3/04817

USPC D14/485-495

(57) **CLAIM**

The ornamental design for a display screen with graphical user interface, as shown and described.

DESCRIPTION

FIG. 1 is a front view of a display screen with graphical user interface showing our new design; and, FIG. 2 is a front view of the display screen with graphical user interface of FIG. 1 shown with additional disclaimed environment.

The broken line showing of the remainder of the user interface and display screen is for environmental purposes only and forms no part of the claimed design.

1 Claim, 2 Drawing Sheets
